UNITED STATES PATENT OFFICE.

MATTHIAS BROCK, OF BOSTON, MASSACHUSETTS, ASSIGNOR TO UNITED SHOE MACHINERY CORPORATION, OF PATERSON, NEW JERSEY, A CORPORATION OF NEW JERSEY.

ART OF MAKING SHOES.

1,406,337.

Specification of Letters Patent. Patented Feb. 14, 1922.

Application filed August 17, 1918. Serial No. 250,267.

To all whom it may concern:

Be it known that I, MATTHIAS BROCK, a citizen of the United States, residing at Boston, in the county of Suffolk and State 5 of Massachusetts, have invented certain Improvements in the Art of Making Shoes, of which the following description, in connection with the accompanying drawings, is a specification, like reference characters on 10 the drawings indicating like parts in the several figures.

This invention relates to the art of making shoes and more specifically to the earlier stages in the process of the manufacture of 15 a shoe during which the upper is both given the shape of the last upon which the shoe is largely manufactured and is also secured to the insole.

Although the invention may be utilized in 20 the manufacture of various types of shoes, which term is herein intended to include boots, slippers and other footwear, it is herein described particularly with reference to the manufacture of Goodyear welt shoes 25 which, according to the prevailing practice, remain upon the last throughout substantially the entire bottoming operation. More specifically, in making a Goodyear welt shoe, an insole is usually tacked to the bottom 30 of the last and then the upper, including the lining and end stiffeners, is assembled upon the last and the upper is pulled over and lasted, thereby imparting to the shoe the shape of the last and, indeed, the 35 shape which the finished shoe is to have. After this shaping, the bottoming of the shoe proceeds.

While, on the one hand, the superior appearance and fit of a Goodyear welt shoe is 40 largely due to the fact that the last remains continuously therein from the time when it is first inserted until the shoe is virtually completed, yet, on the other hand, the direct and indirect expense of providing and maintaining a full equipment of lasts is an increasingly heavy burden for the shoe manufacturer. Hence, it is a primary object of 45 the present invention to reduce the number of operations in the manufacture of a shoe 50 which are performed while it is mounted on the last and, in general, to increase the efficiency of the process of making a shoe.

Accordingly, a very important feature of the present invention is that the upper and

insole, or it may be the sole of a single soled 55 shoe, are secured together before they are assembled upon the last. Thus, the invention, in one aspect, comprises securing off the last a relatively small section of an upper to a sole, whether it be an insole or a 60 turn sole, thereafter mounting the upper and sole thus connected upon a last and then drawing a further section of the upper to the last and securing it to the sole. According 65 to the preferred method of practising the invention, a flange is produced on the heel of the upper and secured to and around one end of the insole and then these assembled parts are mounted, as a single unit, on and drawn to a last, as just described. 70

According to another feature of the invention, one or both of the ends of the upper are molded, shaped or formed to a shape corresponding to that of the last not only before the upper is mounted upon the last 75 but also before the upper is secured to the insole.

In carrying out the invention in the particular manner hereinafter described in detail by way of illustration, the sides of the 80 upper at the heel end of the shoe are molded or shaped and the heel flange formed over metal or metal-faced forms, which may be heated and then the flange is permanently and firmly secured to and around the heel 85 of the insole, all as one continuous operation, after which the last is inserted within the upper and insole unit and then the remainder of the upper is drawn to the last and secured to the insole, for example, in a 90 manner similar to that now carried on in the usual pulling-over and lasting operations, which operations are greatly facilitated by the preliminary molding of the upper just described for the reason that the 95 upper has been given approximately the shape of the last before these operations. As hereinafter described, the toe of the upper may be molded with an upstanding flange at its margin which, after the last has been 100 partially inserted within the upper, may conveniently be seized by grippers such as those commonly used in hand lasting or in pulling over machines.

According to one feature of the invention, 105 after the last has been inserted within the assembled upper and sole, a portion of the margin of the sole is accurately positioned

in predetermined relation to the edge of the last and then the upper is drawn to the last and secured to the sole.

While the invention preferably comprises all of the steps herein described, yet obviously many of the advantages of the invention will be obtained even although some of the steps are modified, omitted or replaced by other corresponding steps now commonly performed. It will be understood, therefore, that the invention comprises not only the complete method herein described but also various novel and useful steps or combinations of steps in the art of making shoes also the article of manufacture, all of which, as well as the scope of the invention, will be defined in the appended claims.

The preferred mode of practicing the invention will now be described in detail in connection with the accompanying drawings, wherein—

Fig. 1 is a side elevation, partly in section, of the toe of a partially molded upper and certain portions of an apparatus which may be conveniently used in shaping it;

Fig. 2 is a perspective view of the complete upper after the toe has been molded;

Fig. 3 is a similar view of the heel of the upper and of a portion of apparatus which may be used in molding and flanging it;

Figs. 4 to 6, inclusive, are longitudinal sectional views, partly in elevation, showing successive steps in the shaping of the heel;

Fig. 7 is a view similar to Fig. 6, showing the stage in the manufacture of the shoe when the flanging of the heel is substantially completed and the insole is about to be applied thereto;

Fig. 8 is a similar view showing the insole secured to the heel flange by an adhesive;

Fig. 9 is a similar view showing the step of inserting lasting tacks for further securing the flange to the insole;

Fig. 10 is a similar view of the shoe after the last has been partially inserted;

Fig. 11 is a perspective view of the shoe as it is being pulled over and toe lasted, and

Fig. 12 is a similar view of the shoe after these operations have been completed.

In carrying out the invention, there is provided, according to the illustrative method, an upper 2 which may comprise the usual elements, such as the leather, or perhaps cloth, upper itself, including a toe cap 4, a lining 5 and toe and heel stiffeners of any suitable type, the heel stiffener being shown at 6 in Fig. 2. This upper may be cut more closely to its final size than is the customary practice. After the parts of the upper have been secured together, the toe is molded or formed to give it substantially the shape of the last upon which the shoe is to be largely manufactured. As a result of this operation, as herein illustrated, the mar-

gin of the upper is left as a molded upstanding flange 8 adapted to be seized readily by the grippers of a pulling over machine. Any suitable molding or shaping means may be used for this purpose. For the purposes of this description, it may be assumed that the method and the general type of apparatus disclosed in my United States Patent No. 1,195,967, dated August 29, 1916, will be employed. As herein shown in Fig. 75 1, the principal shaping parts include an inner mold or former 10, an outer mold or co-operating member 12, the two molds being movable both relatively to each other and also movable together with respect to a table 80 14 and a U-shaped clamp 16 between which the margin of the upper will be yieldingly held. As set forth in the prior patent just mentioned, the toe of the upper, particularly if a certain commonly used type of self-hardening toe stiffener is employed, will be softened by heat or moisture or both before the molding pressure is applied. The inner mold 10 having been drawn away from the outer mold 12 and the clamping members 14 85 and 16 having been sufficiently separated, the toe of the upper is inserted and properly located, by appropriate gages or otherwise, between the respective molds and clamping members. The latter are then relatively actuated to stretch the toe of the upper and to give it approximately its final shape, as indicated in Fig. 1. After the upper has sufficiently set, the wedge 18 supporting the table 14 is retracted slightly 90 whereupon both molds are raised further relatively to the clamping members with the result that the margin of the upper is gradually withdrawn from these members against frictional resistance and, being drawn over the inner lower edge of the member 16, the margin of the upper is shaped as an upright flange 8 (Figs. 2 and 10).

The heel of the upper is next molded. As in the case of the toe, the heel is preferably formed substantially to the shape of the last upon which the shoe is to be manufactured but, as is elsewhere herein more fully explained, it is really overmolded to compensate for whatever reaction takes place. As 110 shown in Fig. 3, the heel molding apparatus comprises an inner mold or form 20, the upper face, or the whole of which, is of metal and which is preferably heated as by an electrical unit 22. Suitable mechanism, a portion of which only is shown, is provided for raising and lowering the mold as required. Co-operating with this inner mold is an outer mold 26 which is shown as sectional and provided with a continuous lining of leather or the like 28. Above the outer mold are wiper plates 30 for breaking down and shaping the heel flange. Preferably, also a neck presser 32 is provided to engage the upper preliminarily adjacent to 115 120 125 130

the lower edge of the heel stiffener, as shown for example in Fig. 4, and to force the upper forwardly and to tilt the ends of the heel stiffener upwardly in the vicinity of the shank of the shoe. The inner mold 20 is movable longitudinally relatively to the outer molding parts 26, 30, 32, thus facilitating the placing of the heel of the upper about the inner mold. The location of the edge of the upper with relation to the face of the mold 20 and laterally may be determined by the eye or by suitable gages, whereupon the upper is drawn to fit snugly about the mold, as shown in Fig. 3. Thereafter, the mold 20 is moved relatively backward to the position indicated in Fig. 4 where the neck presser 32 is shown clamping the upper between itself and the lower portion of the face of the mold, thus, as just described, tilting the ends of the heel stiffener 6 and also the overlying upper materials and forming a pocket to fit the ball of the heel of the wearer. Then, the outer mold 26 is closed around the upper co-operating with the inner mold 20 to shape the sides of its heel. The wipers 30 are then moved inward, and preferably are moved inward and outward several times as indicated by the diagram D in Fig. 6, to break down, iron and shape the inturned heel flange 38 and to produce a sharp break or angle between it and the sides of the heel.

Then, the upper is allowed to remain under pressure within the mold until it has become sufficiently set, whereupon the molds are separated somewhat as shown in Fig. 7, the inner mold 20 being lowered away from the flange 38 a distance somewhat greater than the thickness of an insole and the pressure on the outer mold 26 being relaxed. However, the mold 20 may be moved also slightly forward if desired. It is believed that the upper will be sustained by the outer mold in the position shown in Fig. 7 but other mechanical means or the hand of the operator may also assist in thus sustaining it.

The next step in the process is to locate the insole 40 within the upper and to secure it thereto. The insole, provided as shown in Fig. 7 with a sewing lip or rib and with an adhesive 42 upon its upper face, is now slid into place between the lower face of the flange 38 and the upper face of the mold 20. An adhesive suitable for the purpose is any quick setting asphaltum or pitch such as is often employed for securing shank stiffeners to shoe bottoms. Suitable gages may be provided upon the heel molding machine bearing against the forepart of the insole and insuring its correct location laterally with relation to the upper. After the insole 40 has been thus located the outer mold 26 may again be closed, if desired, and then the inner mold 20 is raised to press and

consolidate the insole firmly against the flange 38, the pressure being resisted by the wipers 30. Instead of or in addition to the adhesive 42, tacks 44 may be driven through the heel flange 38 and the insole 40 and clinched upon the metal face of the mold 20. As shown in Fig. 9, any suitable tool such as an ordinary hand tacker 46 may be employed for this purpose. Before the tacks are driven, the wipers 30 will be withdrawn sufficiently to expose the inner margin of the upper.

It is contemplated that, under some circumstances, it may be considered preferable to locate the heel of the insole upon the inner mold, somewhat as shown in Fig. 8, before the heel flange is broken down and then to shape and iron the flange over the insole during the initial heel molding operation. In that case, the upper face of the mold 20 may be provided with spurs which are pressed into the inner face of the insole and which prevent displacement of the insole during the heel molding and flanging operation. Moreover, in such case, a thin edged metallic plate may be held upon the end of the insole during this operation so as to present a rigid edge over which to form the sharp break or bend in the upper, this plate being withdrawn before the adhesive 42 is applied or the tacks 44 are driven.

In the molding or shaping of the upper, both at the toe and heel, it will usually be preferable to "over mold" the materials, that is to say, the curves of the molds 10, 20 and of their complemental parts will be exaggerated, thus compensating for the elasticity or reaction of the upper materials after they are removed from the molds. Indeed, obviously, if when the upper is applied to the last, it is thus overmolded, less pull thereon is required to shape it finally to the last than would be the case if the upper were undermolded. On the other hand, even if the materials do react considerably after they have been removed from the molds, yet, because they have once been stretched or overmolded as described, they can be more easily drawn down to the last again.

The shoe is now ready for such further pulling over and lasting as may be desired. A last 48 of an ordinary or suitable type is inserted within the assembled upper and insole either by being passed through the top of the shoe or, the insole being bent back at the toe, through the bottom thereof. The heel end of the last is forced well back into the molded heel of the upper and against the heel of the insole. The toe of the last is pressed down as far as can be done conveniently into the pocket formed at the toe of the upper.

As illustrated in Fig. 11, the shoe is pulled over and toe lasted by the use of a machine. For the purposes of this description, it is suf-

ficient to state that the machine employed may be generally of a type now in use and represented by United States Patents Nos. 1,185,949, April 13, 1915, McFeely, and 5 1,137,564, April 27, 1915, Ashton. As illustrated, this "pulling-over" machine includes a heel rest 50, a sole rest 52, side pressers or clamps 54, toe and side grippers or pincers 56, tack blocks 58, tack drivers 60 and toe 10 wipers 61. Preferably, the machine will be provided also with means for correctly locating the forepart of the insole with relation to the edge contour of the last and also with means for holding down the margin of the 15 insole as the upper is drawn to the last. In Fig. 11, this gaging and holding means is shown as fingers 62 each provided with an extension 64 adapted to bear against and align both the edge of the insole and the edge 20 of the last at its bottom. The fingers are provided also with lugs or shoulders 66 constructed and arranged to press down upon the feather of the insole outside the sewing rib. These fingers may be supported in the 25 machine and actuated in any known or suitable manner so as to be withdrawn from engagement with the insole after the upper has been drawn to the last so as not to interfere with the mechanisms which carry the upper 30 over and secure it to the insole.

The last 48 having been inserted within the assembled upper and insole and the insole having been laid down upon the bottom of the last, the shoe is presented to the pulling over and toe lasting mechanism, the flange 8 being entered between the jaws of the grippers 56 and the insole being located on the last by the fingers 62. Because of the preliminary stretching and molding to which 40 the upper has been subjected, very little stress is required to draw the forepart of the upper snugly to the surface of the last. After this step has been accomplished through the action of grippers 56, the fingers 45 62 are withdrawn and the wiping and tack driving mechanisms are actuated to force the upper over the feather of the insole and into the angle between it and the sewing rib. The upper may then be secured in this position 50 by tacks 68 or by both tacks and a toe binder such as the wire 70. This operation may be performed as fully described in said Patent No. 1,185,949. Both the toe and heel lasting having now been completed, the sides may 55 also be lasted, if desired, by hand or by machine, although even for a welt shoe, it is contemplated that some shoe manufacturers will consider it unnecessary to side last a shoe made according to the above described 60 process except as such lasting is effected during the attachment of the welt.

From this point on, the manufacture of the shoe may be completed in any known or suitable manner, the bottom including both sole 65 and heel being applied and secured to the

lasted shoe and then finished as may be desired.

While I have thus described in detail one method of practising my invention, it should be understood that my invention is not limited in its broader aspects to the inclusion of every step described because many of the advantages of the invention can be secured by carrying out a portion only of the several steps of the complete process.

Therefore, what is claimed as new and what it is desired to secure by Letters Patent is:

1. That improvement in the art of making shoes which comprises securing a relatively 80 small section only of an upper to a sole off the last, thereafter mounting the upper and sole thus connected upon the last, and then drawing a further section of the upper to the last and securing it to the sole.

2. That improvement in the art of making shoes which comprise flanging one end of an upper, securing the flange to one end only of a sole but leaving the greater portion of the sole free, thereafter mounting the assembled upper and sole upon a last and then drawing the upper to the last and securing it immediately thereafter directly to the sole.

3. That improvement in the art of making shoes which comprises assembling an upper 95 and a sole off the last on which the shoe is to be manufactured, the sole having approximately the shape and size of the bottom of the last, securing a section of the margin of the upper to the sole, mounting the assembled upper and sole upon said last, then securing a further section of the upper directly at its margin to the sole.

4. That improvement in the art of making 105 welt shoes which comprises assembling an upper and an insole off the last on which the shoe is to be manufactured, flanging the heel of the upper, permanently and firmly securing the heel flange to one end of the insole, thereafter mounting the assembled upper and insole upon said last and then drawing another section of the upper to the last and securing it to the insole.

5. That improvement in the art of making 115 shoes which comprises molding the heel of an upper, including a counter, to a shape corresponding to that of the last on which the shoe is to be manufactured and producing therein a heel flange, inserting the heel of an insole within the upper and against 120 the heel flange, fastening said flange permanently to the insole, inserting said last within the upper and insole thus assembled and then drawing the upper to the last and further securing it to the insole.

6. That improvement in the art of making 125 welt shoes which comprises molding the heel of an upper, including a counter, to a shape corresponding to that of the last on which the shoe is to be manufactured and 130

producing therein an inturned heel flange, inserting the heel of an insole within the upper, pressing the heel of the insole against the heel flange and securing them permanently together, next mounting the assembled upper and insole upon a last and then proceeding with the further manufacture of the shoe.

7. In the art of making shoes, the combination of steps which comprises producing over a form an inturned flange in the margin of an upper, separating the form from the flange, inserting a sole within the upper and against the flange, and then securing it permanently to the flange while the upper still remains around the form.

8. In the art of making welt shoes, the combination of steps which comprises breaking down the margin of the end of an upper and wiping it over the metallic face of a form under heat to produce an inturned flange, separating the form from the flange, inserting the end of an insole within the upper and against the flange, and then through the form pressing the insole against the flange and securing it permanently thereto.

9. That improvement in the art of making shoes which comprises molding the heel of an upper substantially to the shape of the last on which the shoe is to be manufactured, breaking down the margin of the upper and wiping it over the metallic face of a heel form to produce an inturned heel flange, separating the form from the flange, inserting the heel of an insole within the upper and against the heel flange, and then through the form pressing the insole against the flange and securing it thereto under pressure by an adhesive and tacks.

10. That improvement in the art of making shoes which comprises providing the heel of an upper, including a counter, with an inturned flange, assembling the upper and a sole and securing the flange of the upper permanently to and around one end of the sole by a plurality of tacks, next mounting the assembled upper and sole upon a last and then proceeding with the further manufacture of the shoe.

11. That improvement in the art of making shoes which comprises molding the heel of an upper, including a counter, substantially to the shape of the last on which the shoe is to be manufactured but with its curves overmolded and producing in the upper an inturned heel flange, assembling the molded upper and an insole on a metal-faced heel form, securing the flange of the upper to the insole by a plurality of permanent tacks, then removing the work from the form, inserting said last within the upper, and proceeding with the further manufacture of the shoe.

12. That improvement in the art of mak-

ing shoes which comprises molding both the toe and heel of an upper to a shape corresponding to that of the last on which the shoe is to be manufactured, and with an inturned flange at one end, securing a sole to 70 said flange off the last, mounting the upper and sole thus connected upon said last, drawing the upper to the last and securing it further directly to the sole.

13. That improvement in the art of making shoes which comprises molding an end of an upper substantially into lasted shape and while holding it in such shape permanently securing the margin of the molded end portion only to an end of an insole, all before applying the upper to the last on which the shoe is to be manufactured, then inserting the last, drawing the upper to the last and proceeding with the further manufacture of the shoe.

14. That improvement in the art of making shoes which comprises overmolding an end of an upper and forming the margin thereof under heat into lasted shape, then securing it under pressure in lasted relation 90 to and around one end of an insole, next mounting the connected upper and insole on a last and proceeding with the further manufacture of the shoe.

15. That improvement in the art of making welt shoes which comprises manufacturing, as one unit, an upper having an inturned flange and molded to a shape corresponding to that of the last upon which the shoe is to be manufactured and connected to 100 a lipped insole having approximately the shape and size of the last bottom, said insole being secured to the flange of the upper, then inserting said last into said connected upper and insole, drawing the upper to the last and 105 proceeding with the further manufacture of the shoe.

16. That improvement in the art of making welt shoes which comprises molding both the toe and the heel of an upper to a shape 110 corresponding to that of the last on which the shoe is to be manufactured, assembling the upper and an insole off the last, securing a section of the margin of the upper to one end of the insole, mounting the assembled 115 upper and insole upon said last and then drawing the upper to the last and securing the unsecured portion of its margin to the insole.

17. That improvement in the art of making shoes which comprises molding both the toe and the heel of an upper to a shape corresponding to that of the last on which the shoe is to be manufactured and producing therein an inturned end flange, then while holding the upper in such shape permanently securing the flange to the end of an insole, next mounting the assembled upper and insole upon a last and then completing the shoe.

18. That improvement in the art of making shoes which comprises molding both the toe and the heel of an upper to a shape corresponding to that of the last on which the 65
5 shoe is to be manufactured and producing therein an inturned heel flange, permanently and firmly securing the flange to the heel of an insole, then inserting said last within the assembled upper and insole with the toe of 70
10 the insole within the toe of the upper, drawing the upper to the last and securing the remainder of its margin to the insole.
19. That improvement in the art of making shoes which comprises molding the toe of 15
15 an upper substantially to the shape of the last on which the shoe is to be manufactured and with an upstanding margin, flanging the heel of the upper and securing the flange to the heel of an insole, inserting said last 20
20 within the assembled upper and insole with the toe of the insole within the toe of the upper, gripping the upstanding flange and drawing the upper to the last and then securing the toe of the upper to the insole.
20. That improvement in the art of making shoes which comprises molding the toe of an upper substantially to the shape of the last on which the shoe is to be manufactured and with an upstanding flange, producing in 30
30 the heel of the upper an inturned flange, securing said heel flange to the heel of an insole, inserting said last within the assembled upper and insole with the toe of the insole within the toe of the upper, the margin of 35
35 the toe of the insole being positioned in predetermined relation with the contour of the last bottom, then with the parts so positioned gripping the upstanding flange and drawing the forepart of the upper to the last and 40
40 securing its margin to the insole.
21. That improvement in the art of making shoes which comprises connecting together at one end only an upper and a sole off the last on which the shoe is to be manu- 45
45 factured, mounting the connected upper and sole as a unit upon said last, a portion of the margin of the sole being positioned in predetermined relation with the edge of the last bottom, such positioning being effected 50
50 independently of the connection between the upper and the sole, then drawing the upper to the last and securing it to the sole.
22. That improvement in the art of making welt shoes which comprises producing 55
55 an inturned flange in one end of an upper, securing said flange to the end of a lipped insole, mounting the assembled upper and insole upon a last with the free end of the insole within the upper, the margin of said 60
60 end of the insole being positively aligned with the edge of the last bottom, then drawing the upper to the last and securing the unsecured portion thereof to the insole.
23. That improvement in the art of mak- 65
65 ing welt shoes which comprises molding an upper including its stiffening materials over a metallic heel form having a bottom face corresponding to the shape and size of the heel of the insole to be used and having ex- 70
70 aggerated curvatures on its side faces to effect over-molding of the upper to compensate for its reaction from molded position after it has been freed from the molding means, and shaping the margin of the upper over the edge of the metallic form into an 75
75 insole attaching flange, then producing a relative separation of the mold and said flange to provide between them a space within which to insert the heel of the insole, inserting the heel of the insole next to the 80
80 flange, clamping the insole and said flange together and while continuing to hold the molded upper around the heel form, securing the upper by said flange to the insole all around its heel end so that the upper is re- 85
85 strained from reacting from its molded shape after the upper is freed from the molding means, and then removing the upper and insole together and proceeding with the fur- 90
90 ther manufacture of the shoe.
24. That improvement in the art of making welt shoes which comprises molding an upper over a heel form having a bottom face corresponding to the shape and size of the heel of the insole to be used and shap- 95
95 ing the margin of the upper over the edge of the form into an insole attaching flange, then producing a relative separation of the mold and said flange to provide between them space within which to insert the heel 100
100 of the insole, inserting the heel of the insole next to the flange, and securing the upper by said flange to the insole so that the upper is restrained from reacting from its molded shape after the upper is freed from 105
105 the molding means, and then removing the upper and insole together and proceeding with the further manufacture of the shoe.
25. That improvement in the art of making shoes which comprises molding a por- 110
110 tion of an upper to a shape corresponding to that of the last upon which the shoe is to be manufactured, relaxing the molding pressure and then, while still retaining control of the upper, positioning a sole in assembled 115
115 relation thereto off the last and securing the molded upper in lasted relation to the sole.
26. That improvement in the art of making shoes which comprises molding an upper over a form and producing therein an 120
120 inturned heel flange, somewhat relaxing the molding pressure, inserting the heel of an insole next to said flange, re-applying mold- 125
125 ing pressure and securing the flange of the molded upper permanently and in its final relation to the insole.
27. That improvement in the art of making shoes which comprises securing a rela-

tively small section only of the lower marginal portion of an upper off the last to one end only of a sole, thereafter mounting the upper and sole thus connected upon a last, 5 and then securing a further section of the margin of the upper to the sole.

28. That improvement in the art of making shoes which comprises molding one end of an upper off the last with an inturned flange, securing the flange permanently and firmly to and around one end only of a sole, thereafter mounting the upper and sole thus connected upon a last, and securing a further section of the margin of the upper in 15 lasted relation to the sole.

29. That improvement in the art of making shoes which comprises molding an inturned flange at one end of an upper, securing an end of a sole permanently to said 20 flange while the upper is subjected to molding pressure, thereafter mounting the upper and sole thus connected upon a last, and proceeding with the further manufacture of the shoe.

30. That improvement in the art of making shoes which comprises molding the heel end of an upper to a shape corresponding to that of the last on which the shoe is to be manufactured and producing therein an in- 30 turned flange, securing the heel end of an insole permanently to said flange while the insole is firmly pressed thereagainst and while the upper remains under molding pressure, thereafter mounting the upper and in- 35 sole thus connected upon a last and proceeding with the further manufacture of the shoe.

31. That improvement in the art of making shoes which comprises molding one end 40 of an upper over a form to a shape corresponding to that of the last on which the shoe is to be manufactured and producing therein an inturned flange, securing an end of an insole permanently to said flange while 45 the upper still remains around the form, thereafter mounting the upper and insole

thus connected upon a last, and proceeding with the further manufacture of the shoe.

32. That improvement in the art of making shoes which comprises securing one end 50 of an upper to and around one end only of an insole, thereafter mounting the upper and insole thus connected upon a last, gripping unsecured portions of the upper, stretching the upper over the last and securing such 55 unsecured portions to the insole.

33. That improvement in the art of making shoes which comprises securing one end 60 of an upper to and around one end only of an insole, thereafter mounting the upper and insole thus connected upon a last, lasting unsecured portions of the upper along the sides of the shoe, and securing them to the insole.

34. As an article of manufacture, a separate 65 shoe unit adapted for assemblage on a last with other separate shoe units to be connected therewith, comprising an upper molded at one end to substantially the shape which it is to have in the finished shoe and 70 having an inturned end flange permanently and firmly secured to and around one end only of an insole.

35. As an article of manufacture, a separate 75 shoe unit comprising an upper having at one end an inturned flange permanently and firmly secured to and around one end only of an insole having its final shape.

36. As an article of manufacture, a separate 80 shoe unit off the last, adapted for assemblage on the last with other separate shoe units to be connected therewith, comprising an upper molded at its end to substantially the shape which it is to have in the finished shoe and having at its heel end an inturned 85 flange permanently and firmly secured by a plurality of tacks to and around the heel end only of a lipped insole having its final shape.

In testimony whereof I have signed my 90 name to this specification.

MATTHIAS BROCK.
